US0D1109892S

(12) **United States Design Patent** (10) **Patent No.:** **US D1,109,892 S**
(45) **Date of Patent:** **** Jan. 20, 2026**

(54) **HEXAGONAL MODULAR FLORAL ARCH**

(71) Applicant: **Syndicate Sales, Inc.**, Kokomo, IN (US)

(72) Inventor: **Trent A. Harshman**, Galveston, IN (US)

(73) Assignee: **Syndicate Sales, Inc.**, Kokomo, IN (US)

(**) Term: **15 Years**

(21) Appl. No.: **29/870,880**

(22) Filed: **Feb. 7, 2023**

(51) LOC (15) Cl. **08-99**

(52) U.S. Cl.

USPC **D25/100**

(58) **Field of Classification Search**

CLAIM

The ornamental design for a hexagonal modular floral arch, as shown and described.

DESCRIPTION

FIG. 1 is a front right perspective view of the hexagonal modular floral arch incorporating our new design;

FIG. 2 is a back left perspective thereof;

FIG. 3 is a rear view thereof;

FIG. 4 is a front view thereof;

FIG. 5 is a top view thereof;

FIG. 6 is a bottom view thereof;

FIG. 7 is a left view thereof; and,

FIG. 8 is a right view thereof.

1 Claim, 6 Drawing Sheets
